ABSTRACT

A gas collecting main, extruding coextensively of a coke oven battery, has a flexible, heat-resistant web closing one side. An apparatus that is mounted to, or that is movable synchronously with, a coke guide cooperates with the flexible web to provide an opening in the collecting main wherever the apparatus stops so that gases, emitted from a coking chamber when the doors are removed and while pushing coke, are directed into the collecting main only through such opening.

FIG. 3

FLEXIBLE BELT MOVABLE HOOD

BACKGROUND OF THE INVENTION

This invention relates to coke ovens and, more particularly, to method and apparatus for tapping a suction main into which gases, emitted from the coke oven when doors are removed and coke is pushed, are directed and thereby removed from the coke oven battery.

During the pushing of hot coke from a coking chamber of a coke oven battery there evolves a large volume of gases containing dust and other particulate matter that pollute the air since these pollutant gases are not now collected and scrubbed. However, because of the passage and enforcement of more rigid code requirements on air pollution, ways and means are being found to curb the pollution of the environmental air around a coke oven battery. One novel apparatus that is adapted for collecting the pollutant gases evolving during pushing of coke from a coke oven chamber is described hereinafter.

SUMMARY OF THE INVENTION

A first conduit is mounted to means associated with a movable coke guide for collecting smoke and gases during pushing, and a second conduit is fixed to a coke oven battery. A third conduit connects the first and second conduits and covers a finite area portion of flexible belting forming one side of the second conduit. Means is provided for moving the third conduit along with the coke guide, and means is provided for partially detaching the flexible belting in the area beneath the third conduit thereby forming an opening for the gases and smoke to flow into the second conduit; such means also replaces the flexible belting as the third conduit moves.

BRIEF DESCRIPTION OF THE DRAWING

The drawing illustrates one embodiment of the invention wherein:

FIG. 1 is a schematic elevational view of apparatus in accordance with the invention;

FIG. 2 is a view along line II-II of FIG. 1;

FIG. 3 is a schematic view of a portion of a coke oven showing the relation of the apparatus of FIGS. 1 and 2 thereto.

DETAILED DESCRIPTION

Referring to FIG. 1, an elongate gas collecting main 11 is fixed in a suitable location and is coextensive with the length of a coke oven battery 12. The gas collecting main 11 has a generally rectangular shape, as shown in FIG. 2, being comprised of parallel vertical spaced apart side walls 13, 15 and a flat horizontal bottom 17 connecting the side walls 13, 15. The top of the collecting main 11 is open between the toes of oppositely opposed angles 19, 21 mounted securely to the top edges of respective side walls 13, 15.

At regularly spaced apart intervals along the length of the gas collecting main 11, there are transversely extending Tee members 23 which are connected suitably, as by welding, to the angles 19, 21. Thus, there are a plurality of substantially rectangular shaped openings 25 in the top of the gas collecting main 11 through which gases pass entering the main.

Outwardly extending angles 27, 29 are fitted to the side walls 13, 15 respectively, as shown in FIG. 2, and these angles are coextensive with the length of the gas collecting main 11. The angle 27 carries an inverted angle 31 welded thereto, as shown in FIG. 2, which angle 31 forms a track that coacts with a pair of notched or grooved rollers 33, 35.

The rollers 33, 35 are journaled respectively in a hood structure 37 mounted for movement along the length of the gas collecting main 11.

The hood structure 37 comprises a vertical front wall 39 that is generally triangular in shape with its apex at the top and an envelope 41 which is secured to the two sloping edges of the triangular vertical wall 39. The envelope 41 connects to a duct 43 which is shaped about as shown in FIG. 2 and which is connected to a gas conduit 45 by means of a flexible joint 47 of the bellows type. The gas conduit 45 is secured to and communicates with a hood enveloping the coke guide. Internally, there is a butterfly type of damper 49 in the gas conduit 45 about where shown in FIG. 2.

It will be noted that one wall of the duct is journaled to the left hand ends of the rollers 33, 35.

Within the envelope 41 there is another vertical wall 51 that is parallel to the vertical front wall 39, but the interior wall 51 has a large generally triangular opening 53 in it through which gases rising in the gas conduit 45 pass.

The spaced apart vertical walls 39, 51 are interconnected by a plurality of transversely extruding Tee bars or members 55; three Tee bars 55 being on the left and three Tee bars being on the right of the vertical centerline of the front wall 39, as may be noticed by reference to FIG. 1.

At the apex of the front wall 39 and the interior wall 51 there is journaled in each wall respectively another horizontally extending roller 57.

A flat flexible belt 59, which may be made of any suitable material such as asbestos wire woven belting having a silicon coating, extends across the top of the open gas collecting main 11, and it extends from a dead end connection (not shown) at the right hand end of the gas collecting main 11, to the roller 35. The belting 59 passes under roller 35 and up on the surface provided by a pair of oppositely positioned angles 61, 63 mounted to the front wall 39 and to interior wall 51. The belting 59 is also supported transversely by the several Tee bar members 23 and 55.

The belting 59 passes over the upper roller 57 and down the opposite side on the surface of the angles 61, 63 and Tee bar members 53 to the roller 33. The belting passes under the roller 33 and then lies flat on the top of the gas collecting main 11.

Thus, the lower parallel rollers 33, 35 are in upper surface contact with the belting 59 and the upper single roller 57 is in under surface contact with the belting 59.

At the left hand end of the gas collecting main 11, the belting passes via a fixed roller 65, journaled in brackets 67 mounted to an end wall 69 of the gas collecting main 11, and the belting is secured to a resiliently supported end clamp 71; the clamp 71 being resiliently biased by means of a plurality of springs 73 and connecting rods 75 fixed to structure adjacent the gas collecting main 11. Thus, the belting 59 is maintained continually under tension.

From FIGS. 1 and 2 it will be noted that an electric motor 77 of the variable speed type is mounted at one side of the envelope 41, and that the motor shaft carries a sprocket 79. The roller 33 also carries a similar sprocket 81 at one end and an endless drive chain 83 is 5 looped around both sprockets 79, 81.

FIG. 3 shows schematically the relation of the collecting main 11 of the present invention to the coke oven battery 12, to a movable closed coke guide 91 and to a closed quenching car 93 that is moved by a locomotive 95. It will be noted that the collecting main 11 is independently supported on structural columns 97 in such a way that the collecting main 11 is closely adjacent the movable coke guide 91. The coke guide 15 91, of course, moves relative to the fixed collecting main 11.

In operation, the motor 77 is activated so that the roller 33 turns either clockwise (in FIG. 1) to move the apparatus toward the right when the coke guide (gas 20 conduit 45 being fixed to and movable with the coke guide) moves toward the right to the next oven that is to be pushed. When the coke guide is moved into position to receive pushed coke, linkage connected to the coke guide also pivots the butterfly valve 49 about its 25 support shaft 85 to the open position, where shown by dotted outline.

It will be observed that when the apparatus moves with the coke guide, the belting material remains stationary lengthwise, but that the rollers 33, 35, 65 rotate and move respectively over, over, and under the belting at all times. Thus, the belting provides a unique seal on the collecting main that is easily and readily opened, at 30 selected locations, in fact at any location at which the coke guide stops.

It should be recognized by those skilled in the art that in some applications, the apparatus may not be driven by the motor, chain and sprockets described previously, but the apparatus may just move with the coke guide whenever the guide moves along the coke oven 35 battery.

A feature of the invention is that the collecting main remains sealed at all times except at a location where the apparatus is positioned and that position is at a cok- 45 ing chamber that is to be or is being pushed.

A feature of the invention is that the collecting main opens automatically at the coke oven to be pushed and seals automatically after pushing when the coke guide and the apparatus move to the next oven to be pushed.

Although the invention has been described herein with a certain degree of particularity, it is understood that the present disclosure is made only as an example and that various modifications may be made within the scope of the invention defined by what is hereinafter 55 claimed.

What is claimed is:

1. In a coke oven battery having a coke guide with means associated with such guide for collecting smoke and gases emitted during the door removal and pushing of coke from said battery, the improvement comprising:

- a. a first conduit mounted to the means associated with said coke guide for conducting said smoke and gases therefrom;
- b. a second conduit fixed adjacent to and extending coextensively with said coke oven battery, and in-

cluding a continuous flexible belting forming a portion of one side thereof;

- c. a third conduit connected to said first conduit and disposed in close proximity to and over a finite area portion of said flexible belting;
- d. first and second spaced apart parallelly arranged rollers, each being journaled to said third conduit and disposed in upper surface contact with said flexible belting and with said second conduit;
- e. a third roller disposed parallel to and spaced apart from said first and said second rollers and journaled to said third conduit, said third roller being disposed in under surface contact with said flexible belting;
- f. a motor mounted to said third conduit;
- g. a driving sprocket mounted to said motor;
- h. a driven sprocket mounted to one of said first and second rollers;
- i. a drive chain looped around said sprockets and providing a driving connection to said roller whereby when said motor is actuated said third conduit moves relative to said second conduit; and
- j. means cooperating with said third conduit for partially detaching said flexible belting in the area beneath said third conduit and forming an opening into said second conduit, said means being adapted for replacing said flexible belting when said third conduit moves along said battery and for continuing to so open said second conduit as said third conduit moves.

2. The apparatus of claim 1 including:

- a. a flexible bellows-like sleeve connected to both said first and said third conduits.

3. The invention of claim 1 including:

- a. damper means in said first conduit that is operable to open and close said conduit to the flow of smoke and gases in said first conduit.

4. In a coke oven battery having a coke guide with means associated with said guide for collecting smoke and gases emitted during the door removal and pushing of coke from said battery, the improvement comprising:

- a. a first conduit mounted to the means associated with said coke guide for conducting said smoke and gases therefrom;
- b. a damper mounted in said first conduit that is operable to open and close said conduit to the flow of smoke and gases in said first conduit;
- c. a second conduit fixed adjacent to and extending coextensively with said coke oven battery and including a continuous flexible belting forming a portion of one side thereof;
- d. a plurality of structural members on said second conduit forming a skeletal frame on which said flexible belting is supported;
- e. a third conduit connected to said first conduit and disposed in close proximity to and over a finite area portion of said flexible belting;
- f. first and second spaced apart parallelly arranged rollers, each being journaled to said third conduit and disposed in upper surface contact with said flexible belting and with said second conduit;
- g. a third roller disposed parallel to and spaced apart from said first and said second rollers and journaled to said third conduit, said third roller being

- disposed in under surface contact with said flexible belting;
- h. means fixing one end of said flexible belting and means resiliently biasing the other end of said flexible belting whereby said flexible belting is continually under tension;
- i. a motor mounted to said third conduit;
- j. a driving sprocket mounted to said motor;
- k. a driven sprocket mounted to one of said first and said second rollers;
- l. a drive chain looped around said sprockets and providing a driving connection to said roller whereby when said motor is actuated said third

conduit moves relative to said second conduit; and

m. a flexible bellows-like sleeve connecting said first and third conduits.

5. The apparatus of claim 4 including:

- a. a skeletal frame in said third conduit disposed between said first and said third rollers on which said flexible belting is supported.

6. The apparatus of claim 5 including:

- a. a skeletal frame in said third conduit disposed between said second and said third rollers on which said flexible belting is supported.
